(57) **CLAIM**

The ornamental design for a top sizer clip, as shown and described.

DESCRIPTION

FIG. 1 is a top, front perspective view of a top sizer clip showing our new design shown in condition of use;

FIG. 2 is a side and end perspective view thereof;

FIG. 3 is front elevation view thereof, with the back being a mirror image thereof;

FIG. 4 is a top plan view thereof;

FIG. 5 is a bottom plan view thereof; and,

FIG. 6 is a right side elevation view thereof, with the left side being a mirror image thereof.

The broken line showing of a portion of a garment hanger is for illustrative purposes only and forms no part of the claimed design.
